RAILROAD TANK CAR

George W. Patch, Jr., White Plains, N. Y., and James G. Van Vleet, Milwaukee, Wis., assignors, by mesne assignments, to Union Carbide and Carbon Corporation, a corporation of New York

Application May 21, 1946; Serial No. 671,230

4 Claims. (Cl. 105—357)

1

This invention relates to railroad tank cars for transporting liquefied gases having boiling points at atmospheric pressure below 133° K. and more particularly to an improved construction of a double-walled tank car for transporting liquefied gases such as liquid oxygen and liquid nitrogen and in which a space between the inner vessel and outer shell is filled with a powdered insulating material and preferably also evacuated of air.

Tank cars for the storage and shipping of liquefied gases such as liquid oxygen which have been constructed and used consisted of an inner vessel surrounded by an outer shell with the intervening space filled with powdered insulation and evacuated to a very low pressure. In these cars the inner vessel was supported by rods from a frame member and both the inner vessel and outer shell were supported directly over auxiliary bolsters on the car frame, which auxiliary bolsters were located inwardly of the main bolsters. These tank cars were also provided with end-thrust rods and side-sway rods anchored between the inner vessel and outer shell to enable the inner vessel to resist projectile action when the car was accelerated and to prevent side-sway of the inner vessel. The outer diameter of the shell and its length are limited according to standard railroad car width and length.

An increase of the liquid holding capacity of a tank car is very favorable to shipping costs, therefore a principal object of the invention is to provide a construction that permits a larger liquid holding capacity while still allowing the vessel to be mounted within a standard box car and without a reduction of the insulation efficiency. Further objects of the invention are to provide an improved tank car construction for liquefied gases which eliminates the use of auxiliary bolsters and thus reduces the weight of the car for a given volumetric capacity; which supports the inner vessel from the outer shell at points between the supports for the outer shell to employ the outer shell as a beam in bending; in which the main weight of the entire vessel may be supported directly on the main bolsters of the car; and which provides an improved outer shell head construction having a minimum weight with adequate strength to resist the end-wise forces of the loaded inner vessel.

These and other objects of the invention will more fully appear from the following description taken with the accompanying drawings, in which

Fig. 1 is an elevational view of an exemplary tank car without external housing and embody-

2

ing features of the invention with parts broken away to show details thereof;

Fig. 2 is an end view of the tank car of Fig. 1 with portions broken out;

Fig. 3 is a view of a fragmentary section taken along the line 3—3 of Fig. 2; and

Fig. 4 is a fragmentary sectional view of one of the load rod supports 16.

Referring to the drawing, the tank car comprises an inner liquid holding vessel 10 mounted within an external shell 11 in a manner to provide an insulating space 12 completely about the liquid vessel 10. The space 12 is preferably filled with a finely divided insulating powder and subjected to a vacuum of about 100 microns. The inner vessel 10 is supported by the outer shell 11 in a manner to load the outer shell as a beam and create bending forces therein. The supports for the inner vessel comprise a girth band 13 passing under the liquid vessel and suspended on each side by load rods 14. The load rods are secured to blocks 15 fastened to the upper ends of the band 13 and the rods pass upward through the insulation space 12 and the outer shell 11 through compression tubes 16 which extend upwardly from the outer shell 11 and are secured gastightly thereto. As shown in Fig. 4, the upper ends of the compression tubes 16 are provided with flat surfaces or flanges 26 on which lock nuts 17 are threaded onto the rods 14 to bear. The lock nuts 17 are covered by caps 18 which are secured to the flat surfaces of the compression tubes in a gastight manner. Reinforcing plates 19 may be welded to the outer surface of the shell 11 around the compression tubes 16 in order to distribute the load. The outer shell is also preferably provided with two stiffening rings 20 which are close to and straddle the load rods 14. These rings are made sufficiently strong to prevent the vacuum shell from deforming under the combined effect of the vacuum and the weight of the liquid vessel.

The shell 11 is supported over the main bolsters 21 of the car frame F by box-like legs 22 which therefore transmit the weight of the liquid container, the shell 11, and the insulation in the space 12 through the car floor 23 directly to the main bolsters 21. Stiffener rings 24, similar to rings 20, are welded to the inner surface of the shell 11 directly above the legs 22 to prevent deformation of the shell under the force of the vacuum and the bending load to which it is subjected. Both side-sway and vertical displacement of the inner vessel 10 with respect to the shell 11 is prevented by means of four side-sway rods

25, two of which are disposed at each end of the vessel. The outer end of each rod 25 is retained as in Fig. 4 by lock nuts 17 bearing on a surface 26 at the outer end of a short compression tube 27 secured at the head of the outer shell. The nuts are covered by caps 28 secured gastightly to the compression tubes. The inner ends of the sway rods 25 are secured to blocks 29 which are welded near the center of the head of the inner vessel. Since the rods 25 are disposed substantially 45° downwardly from the horizontal, they control side-sway of the inner vessel as well as any tendency for vertical movement.

Longitudinal displacement of the inner vessel 10 relative to the outer shell 11 is controlled by impact rods 30 of which there are four disposed at each end. The outer end of each impact rod 30 has threaded thereon lock nuts 31 (Fig. 3) which bear on a flat flange surface 32 mounted at the outer end of a compression tube 33. The nuts 31 are covered by a cap 34 which is gastightly secured to the flange 32. The inner ends of the impact rods are secured to blocks 35 that are welded to the outer cylindrical surface of the inner vessel 10. The compression tubes 33 pass through the heads of the outer shell 11 and are gastightly welded thereto. Each tube 33 extends inwardly a short distance and is positioned between two radially arranged stiffening ribs 36 which are shaped to fit inside of the head of the shell and extend from a ring 37 secured to the center of the head to the outer one of stiffening rings 24. The ribs 36 are welded at their outer ends to the rings 24. The extension of the ribs 36 until they butt against the outer stiffener ring 24 greatly increases the strength of each head and its ability to resist the impact loads transferred thereto by the impact rods 30. The entire head construction can be made lighter and still have adequate strength.

Relative movement between the shell 11 and the car frame is prevented by four shear plates 38 which have a T-shaped cross-section, the flanges of which are welded to the shell, and the webs of which are secured to the floor 23 of the car by rivets 39. The floor plate 23 transmits the forces of endwise impact to the center sill 40 of the car. The shear plates 38 are preferably positioned inwardly of the legs 22.

The employment of the shell 11 as a beam for supporting the liquid vessel 10 to allow supporting of the shell directly over the main bolsters of the car eliminates the need for special auxiliary bolsters and under-framing. Such auxiliary bolsters and under-framing represent considerable weight and cost. The load rods 30 are not parallel to the horizontal axis of the vessel but are inclined outwardly therefrom at an angle which is preferably about 5°. The purpose of this angle is to control the direction of the resultant force transmitted through the block 35 to the wall of the vessel 10 so that there is no tendency to deform such wall. If the rods 30 were parallel to the main axis there would be a tendency for the block 35 to tilt inwardly and deform the vessel wall.

The tank car is also provided with auxiliary apparatus of the customary type which is not illustrated in the drawings since it forms no part of the present invention. For example, it is customary to provide liquid withdrawal lines leading from the bottom of the inner vessel and passing through the insulation space to a point external of the outer shell, a gas vent line which

may have connected thereto a safety pressure relief device and atmospheric venting means, and means for measuring or observing the height of liquid content in the vessel. The outer shell 11 is usually provided with a means for evacuating the insulation space, for example, a vacuum pump connection, and with a man-hole having a sealing cover 41 at the top of the shell for access to the interior and for filling the insulating space with insulating material.

While a particular embodiment of the invention has been described and illustrated, it will be understood that the invention may be otherwise embodied and practiced without departing from the principles or scope of the invention. Thus it is contemplated that the principles of the invention may be embodied in tank vehicles other than railroad tank cars such for example as road vehicles, particularly when vacuum type insulation is employed.

What is claimed is:

1. In a double-walled insulated tank vehicle including an elongated inner vessel for holding a liquefied gas, an outer shell surrounding and spaced from said inner vessel to provide an intervening insulation space containing an insulating medium which provides substantially no support for the inner vessel, and a vehicle frame having main bolsters near each end; the combination therewith of shell supports secured near each end to said outer shell and to said vehicle frame substantially directly over said main bolsters, said shell supports being constructed to provide substantially the entire vertical support for said shell and contents; inner vessel suspension means anchored directly to upper portions of the wall of said outer shell at two spaced transverse planes located between said shell supports; and reinforcing rings for the shell at said planes, there being no connection between the outer shell and said vehicle frame at the region of said suspension means and reinforcing rings whereby the inner vessel is supported vertically solely from the outer shell.

2. In a double-walled insulated tank vehicle including an elongated inner vessel for holding a liquefied gas, an outer shell surrounding and spaced from said inner vessel to provide an intervening insulation space containing an insulating medium which provides substantially no support for the inner vessel, and a vehicle frame having main bolsters near each end; the combination therewith of shell supports secured near each end to said outer shell and to said vehicle frame substantially directly over said main bolsters, said shell supports being constructed to provide substantially the entire vertical support for said shell and contents; inner vessel suspension means anchored directly to upper portions of the wall of said outer shell at two spaced transverse planes located between said shell supports; reinforcing rings for the shell at said planes; dished heads forming the ends of said shell; at least one reinforcing ring secured to the inside wall surface of the shell adjacent the shell supports near each head; reinforcing ribs radially disposed and secured to the inside wall of each end head, said ribs extending to and being welded to said reinforcing rings; and end thrust rods for preventing relative endwise movement of the inner vessel, said rods being anchored at their inner ends to the side wall of said inner vessel and adjustably secured at their outer ends to securing members in the end heads of said

outer shell, said members being secured respectively adjacent said reinforcing ribs.

3. A double-walled insulated tank car according to claim 2 in which said end thrust rods are inclined outwardly with respect to the horizontal axis of the vessel at an angle of approximately 5 degrees to said axis.

4. In a double-walled insulated tank vehicle including an elongated inner vessel for holding a liquefied gas, an outer shell surrounding and spaced from said inner vessel to provide an intervening insulation space containing an insulating medium which provides substantially no support for the inner vessel, and a vehicle frame below the shell, said vehicle frame constituting the main under-frame of the vehicle exclusive of said shell, and being constructed to carry the weight of said shell and contents; the combination therewith of shell supports secured near each end to said outer shell and to said vehicle frame, said shell supports being constructed to provide substantially the entire vertical support

for said shell and contents; two pairs of suspension members anchored directly to upper portions of the wall of said outer shell at two spaced transverse planes located between said shell supports; and reinforcing rings for the shell at said planes, there being no connection between the outer shell and said vehicle frame at the region of said suspension means and reinforcing rings whereby the inner vessel is supported vertically solely from the outer shell.
